UNITED STATES PATENT OFFICE.

WALTER P. LIMACHER, OF PASADENA, CALIFORNIA.

DEVICE FOR ATTACHING NIPPLES, CAPS, AND THE LIKE ON CONTAINERS.

1,319,297.

Specification of Letters Patent. Patented Oct. 21, 1919.

Application filed April 22, 1919. Serial No. 291,876.

To all whom it may concern:

Be it known that I, WALTER P. LIMACHER, a citizen of the United States, residing at Pasadena, in the county of Los Angeles and 5 State of California, have invented new and useful Improvements in Devices for Attaching Nipples, Caps, and the like on Containers, of which the following is a specification.

10 My object is to make a device for attaching soft nipples, caps and the like to containers, and my invention consists of the novel features herein shown, described and claimed.

15 Figure 1 is a perspective illustrating the operation of applying a nursing nipple to a bottle with an attaching device embodying the principles of my invention.

Fig. 2 is a view analogous to Fig. 1 and 20 showing the nipple applied to the attaching device ready to be removed from the bottle.

Fig. 3 is a vertical diametrical sectional detail showing the operation of applying 25 the nipple to the bottle.

Fig. 4 is a side elevation of the attaching device.

Fig. 5 is a top plan view of the attaching device as seen looking in the direction indicated by the arrow 5 in Fig. 4.

Referring to Figs. 4 and 5, the details of the attaching device are as follows:

The flat annular band 1 has a central bead 2 for stiffening the band and forming a 35 handhold, and the band is large enough to pass freely over the head of the bottle. Spring fingers 3 extend from one edge of the band 1, said fingers being equally spaced apart all the way around the band, and 40 said fingers being of considerable length, and the free ends 4 of the fingers being slightly bent outwardly.

The milk bottle 5 is preferably a straight bottle having a bead 6 around its head. The 45 nursing nipple 7 is bell shaped and has an inwardly extending bead 8 around its lower edge. The nipple is made of soft rubber

and is normally smaller than the head of the bottle. The attaching device is inserted downwardly until the band 1 passes below the bead 6 and then continued downward movement of the band 1 causes the fingers 3 to engage the bead 6, and the bead 6 presses the fingers outwardly. The nipple 5 is placed in position so that the ends 45 4 of the fingers 3 engage above the bead 8 and make a slightly hooked connection, then continued downward movement of the device will pull the bead 8 over the bead 6, as shown in Fig. 3 and finally as shown in 60 Fig. 2, and then the device will pass downwardly and the fingers will pull out of the bead 8 and the nipple is applied to the bottle and the attaching device may be removed by lifting the bottle upwardly. A 65 rubber cap or closure may be applied in the same way.

Various changes may be made without departing from the spirit of my invention as claimed.

I claim:

1. The combination with a milk bottle having a large open end and a nursing nipple adapted to fit the large open end, of an annular band adapted to fit loosely around 75 the bottle and having an outwardly extending bead forming a handhold, and spring fingers extending from the annular band and adapted to engage the head of the milk bottle and to fit inside of the nursing nipple 80 and pull the rim of the nipple over the head of the bottle.

2. The combination with a container having an open end and a soft nipple or cap, of an annular band adapted to fit loosely 85 around the container, and spring fingers extending from the annular band and adapted to engage the head of the container and to fit inside of the nipple or cap and pull the rim of the nipple or cap over the 90 head of the container.

In testimony whereof I have signed my name to this specification.

WALTER P. LIMACHER.
